PULL FOR A SLIDE FASTENER

Everett M. Warren and Allan O. Swan, Meadville, Pa., assignors to Talon, Inc., a corporation of Pennsylvania

Filed Oct. 5, 1964, Ser. No. 82,038

Term of patent 14 years

(Cl. D17—8)

Fig. 1

Fig. 2

Fig. 4

Fig. 5

FIG. 1 is a perspective view of a pull for a slide fastener showing our new design;

FIG. 2 is a plan view of the same;

FIG. 3 is a side view of the same;

FIG. 4 is a top end view of the same; and

FIG. 5 is a bottom end view of the same.

The broken line showing of a slider for a slide fastener is for illustrative purposes only.

We claim:

The ornamental design for a pull for a slide fastener, substantially as shown and described.
